United States Patent Office.

JOSIAH WARD CHILDS, OF CINCINNATI, OHIO.

Letters Patent No. 66,948, dated July 23, 1867.

IMPROVED SASH-FASTENING.

The Schedule referred to in these Letters Patent and making part of the same.

TO ALL WHOM IT MAY CONCERN:

Be it known that I, JOSIAH WARD CHILDS, of Cincinnati, Hamilton county, and State of Ohio, have invented a new and useful Improvement in Sash-Fasteners, of which the following is a full and clear description, reference being had to the accompanying drawings, forming a part of this specification.

Figure 1 is a perspective view of a window-frame and sash with my improved fastener attached.

Figure 2 represents one form of my improved fastener, constructed with a view to great security.

Figure 3 represents a simple form of fastener, and its operation in securing the sash in any desirable position.

My invention relates to a window-fastener so constructed that it will prevent rattling or shaking of the sash in the frame of the window; also fastening the sash either up or down.

A is the window-frame, in which moves the sash B. The construction of the most simple fastener is represented in fig. 3. It is composed of the sliding-plate *a* and guides *b*. The sliding-plate *a* is of metal, of suitable form, is perforated with the diagonal slots *c*. Guides *b* pass through slots *c*, and at the same time hold plate *a* in contact with frame A. The edge of sliding-plate *a*, next to sash B, is turned up, forming lip *a'*, which comes in immediate contact with the sash. A handle, *a''*, projects from lip *a'*. Pin *d* is secured in the sash in line with lip *a'*. When the sash is down, the pin *d* engages the lower end of lip *a'* of sliding-plate *a*. In attempting to raise the window without throwing diagonally backwards the sliding-plate *a*, lip *a'* acts upon the sash as one face of a wedge. The same is the case when the sash is raised, and pin *d* rests upon lip *a'*, (shown in red in fig. 1 and fig. 3.) The weight of the window presses the wedge-shaped parts of sliding-plate *a* between guides *b* and the sash, thus effectually securing the window open, and at the same time preventing rattling. For railroad cars or vehicles of any description the simple form of fastener, as above described, is very desirable.

A more secure fastener, embodying my improvement, is shown in detail in fig. 2. Plate *e*, having the diagonal slot *f*, is secured to the inside of window-frame A. A rib, *g*, projects from the back of plate *e*, runs parallel to slot *f*. Wedge *h* moves freely upon rib *g*, guided by handle *k*, which passes through slot *f* pivoted to plate *e*. Immediately over handle *k* is latch *l*. When it is desired to secure the sash down, the wedge *h* is moved down rib *g* till its lower end or point *h'* bears upon step *m* in sash, as shown in Figure 4. The latch *l* is thrown down, engaging the handle *k*, effectually locking the sash down. When the window is open, the lower rail of the sash may rest upon the top or butt end of wedge *h*; or, when it is desirable to have the window partly open, the wedge *h*, being between the sash and rib *g*, holds the sash in position. One or more fasteners may be used upon each sash, two being necessary where much jar is encountered.

Having fully described my improved sash-fastener, and the mode of operating it, I make the following claims:

1. The slotted sliding-plate *a*, thumb-piece *a''*, slots *c*, and guide-pins *b*, constructed and arranged as above described and for the purpose set forth.
2. The plate *e*, latch *l*, in combination with sliding-wedge *h*, as above described and for the purpose set forth.

JOSIAH WARD CHILDS.
